UNITED STATES PATENT OFFICE.

JAMES M. MAHER, OF FREMONT, NEBRASKA.

STREAM-DEFLECTOR.

1,378,967.

Specification of Letters Patent.

Patented May 24, 1921.

Application filed September 18, 1920. Serial No. 411,093.

To all whom it may concern:

Be it known that I, JAMES M. MAHER, a citizen of the United States, residing at Fremont, in the county of Dodge and State of Nebraska, have invented certain new and useful Improvements in Stream-Deflectors, of which the following is a specification, reference being had therein to the accompanying drawing.

- 10 The invention relates to stream deflectors and has for its object to provide a device of this character for preventing streams of water from cutting away the banks at any particular point.
- 15 A further object is to provide a device of this character which not only protects the low stream bank adjacent to the water's edge, but provides a safeguard for the high bank contiguous to the low bank.
- 20 A further object is to provide a stream deflector comprising a float held spaced from the bank by metallic braces, the outer ends of which are pivotally connected substantially centrally of the float and their inner ends anchored to the low bank at spaced points. Also to provide a cable connection extending from the forward end of the float to the low bank for preventing displacement of the float.
- 25 A further object is to provide a cable connection between the float and the high bank, said cable connection not only forming a holding means for the float but forming means over which brush may be caused to slide to a point adjacent the float, thereby causing said float to sink and preventing movement of sand and causing a collection of sand for building up the bank. Also to provide steel pilings carried by the float
- 30 which pilings sink into the stream bed as the float submerges.

With the above and other objects in view the invention resides in the combination and arrangement of parts as hereinafter set forth, shown in the drawings, described and claimed, it being understood that changes in the precise embodiment of the invention may be made within the scope of what is claimed, without departing from the spirit

50 of the invention.

In the drawings:—

Figure 1 is a plan view of the stream showing the device secured to one bank thereof.

55 Fig. 2 is a sectional view taken on line 2-2 of Fig. 1.

Referring to the drawings, the numeral 1 designates a stream and 2 and 3 the low and the high bank thereof. Where a stream bank has been cut away by the water as at 4, and it is desired to deflect the stream and at the same time cause an accumulation of sediment, sand and the like, the float 5 which is provided with forward downwardly extending pilings 6 is placed adjacent the bank portion 4 and held spaced from said bank by means of metallic bars 7 and 8. The outer ends of the bars 7 and 8 are pivoted on a centrally disposed bolt 9 which passes through the float 5. The bar 7 extends under the float and the bar 8 over the float. The inner ends of the bars 7 and 8 are spaced from each other and are provided with eyes 10 which pass over stake 11, said stake being additionally braced by anchoring stakes 12. Bars 7 and 8 are anchored on the low bank 2 and it will be seen by having their inner ends spaced and staked that the float 5 will be held in position adjacent the bank. A cable 13 is connected to the float 5 as at 14 adjacent its forward end, said cable having its other end connected to a stake 15 on the low bank, which stake 15 is anchored to anchoring stakes 16 for additionally bracing the same. 85 Cable 13 forms means for holding the float 5 against pivotal action as the stream flows in the direction of the arrow a.

Connected to the float 5 is a cable 18, which cable has its other end connected to the stake 19 on the high bank 3 and if so desired anchoring means 20 may be provided for the stake 19 for additionally bracing the same.

The float 5 is primarily used as a means 95 or base to which to attach the bars 7 and 8 and the cables 13 and 18. The bar 8 serves as a track on which bunches of brush 21 may be attached by loops or otherwise which bunches are carried outwardly on the bar 100 8 by the current of the river, the direction of travel being down stream, this rod will be loaded first, and as the weight of the brush increases adjacent the float, the float will sink. The brush will occupy all of the 105 space of the full length of the bar 8 which is anchored to the low bank and it will cause the moving sand to pile up against the brush and provide an embankment which causes the water to recede back from where it has 110 been cutting the low bank. When the float has sunk and carried the brush on the bar

8 down to the bottom of the stream, the cable 4 which is on the high bank is loaded with brush 22 and the brush is carried outwardly until it contacts with the float. 5 The brush placing operation being continued until the space between the float and the edge of the high bank is entirely filled with brush; this being done for the purpose of protecting the high bank and 10 causing the collection of the movable sand, thereby building up the high bank as well as the low bank, the high bank being protected during high water.

From the above it will be seen that a 15 stream deflector and bank builder is provided, which is simple and one which may be easily placed in position and applied at a minimum cost.

The rear end of the float 5 is provided with 20 sharpened pile 6^a, which also becomes embedded in the bottom of the stream as the float settles for additionally preventing the displacement of the float.

It will be seen that by providing one or 25 more rigid members, one end of which is fastened to a float out in the stream, and the other end fastened to a solid piling or other member on the bank of the stream, the float to which the outer ends of said 30 rigid members are fastened is held in position by said rigid members and by the cables which are fastened to the float and to the bank, said cables being up-stream in relation to the float, thereby preventing pivotal action of the float. By so securing the 35 float it will be seen that the float will not only be rigidly held but that the rigid members and the securing cables will be so positioned in relation to the current, that when 40 brush or other material is placed on the said rigid members and the cables, the current carries said brush or other material out toward the outer end of the deflector. In this manner it will be seen that the invention 45 does away with the usual method wherein it is necessary for men to go out into the current to place the brush or other material on the deflector.

To place the float in position, one end of 50 the cable is secured to the float and the other end secured on the bank of the stream. Then the ends of the rigid members are connected to the float, the float forced outwardly and the other ends of the rigid members are then secured on the bank of the stream. 55 The float is held by the cable and the rigid members keep the float out in the current away from the bank of the stream. The cables and rigid members inclining at 60 an obtuse angle to the current so that brush and other material will be carried outwardly by the current as said brush or material comes in contact with the water.

It will be seen that a current deflector is

provided which may be handled by one man 65 if so desired, and one wherein the necessity of entering the water to attach brush and other material is obviated.

By providing the T-shaped anchorings for the rigid members and the cables, it will be 70 seen that said members are securely anchored and in such a manner that they will not interfere with the increasing inclination of the rigid members and the cables as the float moves downwardly incident to 75 the weight of the brush and material.

The invention having been set forth what is claimed as new and useful is:—

1. A stream deflector comprising a float having downwardly projecting piling, metallic bars having their inner ends anchored at spaced points to the stream bank and their outer ends pivoted centrally of the float, cables extending from the float to the stream bank, said cables and metallic bars 85 forming means for guiding bunches of brush to a point adjacent the float for causing said float to sink and for causing the bank to build up incident to the shifting of sand and sediment. 90

2. A stream deflector comprising a float having downwardly projecting piling, metallic bars having their inner ends anchored at spaced points to the lower bank of the stream, said metallic bars forming means 95 for receiving and guiding bunches of brush to points adjacent the float and the bank for causing said float to sink and forming collecting means for shifting material, a cable connected to the forward end of the float 100 and to the low bank for holding the float against pivotal action on the metallic bars incident to the direction of current, a cable connected to the float and to the high ground, said cable forming means over 105 which bunches of brush may be guided and built up so as to protect the high bank during high water.

3. A stream deflector comprising a float, said float being held spaced from the bank 110 by means of rigid members, said rigid members being connected to the float and to the bank and inclining from the float to the bank in an up-stream direction, and cable means connected to the up-stream end of the 115 float and inclining in up-stream direction and connected to the bank, said rigid members and cable connections forming holding and guiding means whereby brush and material when placed on the same will be moved outwardly in the direction of the float by 120 the current of the stream, and T-shaped anchoring means for the rigid member and the cable connection on the bank of the stream. 125

In testimony whereof I hereunto affix my signature.

JAMES M. MAHER.
